(57) **CLAIM**

The ornamental design for a sunroof drain cleaning set, as shown and described.

DESCRIPTION

FIG. 1 is a perspective view of an injection attachment, shown separately for ease of illustration;

FIG. 2 is a front view thereof;

FIG. 3 is a back view thereof;

FIG. 4 is a side view thereof;

FIG. 5 is a side view thereof;

FIG. 6 is a top view thereof;

FIG. 7 is a bottom view thereof;

FIG. 8 is a perspective view of a funnel attachment, shown separately for ease of illustration;

FIG. 9 is a side view thereof;

FIG. 10 is a side view thereof;

FIG. 11 is a bottom view thereof;

FIG. 12 is a top view thereof;

FIG. 13 is a back view thereof;

FIG. 14 is a front view thereof; and,

FIG. 15 is a perspective view of a sunroof drain cleaning set showing my new design.
